UNITED STATES PATENT OFFICE.

HORATIO H. NEWMAN, OF SANDERSVILLE, GEORGIA.

TWO-CYCLE EXPLOSIVE-ENGINE.

1,072,766.

Specification or Letters Patent. Patented Sept. 9, 1913.

Application filed August 12, 1912. Serial No. 714,673.

To all whom it may concern:

Be it known that I, HORATIO H. NEWMAN, a citizen of the United States, residing at Sandersville, in the county of Washington and State of Georgia, have invented certain new and useful Improvements in Two-Cycle Explosive-Engines; and I do hereby declare the following to be a full, clear, and exact description of the invention, such 10 as will enable others skilled in the art to which it appertains to make and use the same.

My invention relates to improvements in two-cycle explosive engines, and it consists 15 in the constructions, combinations and arrangements herein described and claimed.

An object of my invention is to provide an improved two-cycle explosive engine adapted to draw in a full charge of explosive mixture and to operate efficiently under 20 all practical conditions.

A further object of my invention is to provide a simple and practically noiseless two-cycle explosive engine in which all 25 parts are readily accessible, and which insures the automatic lubrication of all moving parts.

In the accompanying drawings forming a part of this application, in which like numbers designate like parts in all the views: 30 Figure 1 is a vertical axial section illustrating one embodiment of my invention; and Figs. 2 and 3 are similar views on a reduced scale, showing the position of the parts during the exhaust and at the beginning of the admission, respectively.

Referring to the drawings, 1 indicates a water-cooled power cylinder provided with an ignition device 2, and with inlet and 40 exhaust ports 3 and 4, respectively; a sleeve 5 being slidably mounted in said cylinder 1, and provided with inlet and exhaust ports 6 and 7 adapted to coöperate with the corresponding cylinder ports 3 and 4. A power 45 piston 8 is reciprocatingly mounted in said sleeve 5 and provided with an inclined upper edge 9 adapted to coöperate with the sleeve ports 6 and 7; said piston being hollowed out to form a flange 10 provided with a port 11 for coöoperating with the sleeve port 7. An eccentric 12 is shown set on the engine shaft 13 at 45° rearwardly of the main engine crank 14, and operatively connected to said sleeve 5 for reciprocating the 55 latter.

The operation of my invention is as fol-

lows:—During the entire power stroke of the piston 8, the sleeve ports 6 and 7 are covered by said piston; the exhaust ports 11, 7, and 4 registering at the completion of the power stroke to permit a prompt exhaust of the products of combustion. During the continued outward movement of the power piston 8, the flange 10 thereof covers the sleeve port 7, and the inclined upper cylinder edge uncovers the sleeve port 6 which is then in registry with the cylinder inlet port 3. Upon further outward movement of the power piston 8, the sleeve 5 is shifted by its eccentric 12 to cover the cylinder exhaust port 4; the ports 3 and 6 remaining in registry during the entire remaining outward movement of said piston 8. The displacement of the piston 8 and sleeve 5 in the cylinder insures the efficient drawing in of an explosive charge, which is also augmented by the contraction of the residual products of combustion due to the subtraction of heat therefrom by the water-cooled cylinder walls; in this operation, the 50 indrawn charge will be confined mainly within the relatively cool portion of the sleeve 5 which has not been subjected to the explosion temperature of the preceding charge. During the entire in-stroke of the power piston 8, the latter coöperates with the sleeve 5 to maintain the inlet and exhaust closed, and the relatively-cool explosive mixture is compressed. Ignition then takes place, and the above steps are 55 repeated.

As shown in the drawings, the open-ended sleeve 5 is constructed to extend within the crank casing 15 during its outward stroke; thereby providing a simple 60 and certain means for efficiently lubricating all of the moving parts by the splash system.

I have illustrated and described preferred and satisfactory constructions, but changes could be made within the spirit and scope 65 of my invention.

I claim:

1. In a two-cycle explosive engine, the combination of a power cylinder, a sleeve 70 slidably mounted in said cylinder, said sleeve and cylinder being provided with co-operating admission and exhaust ports, a power piston reciprocatingly mounted within said sleeve and provided with a port 75 coöoperating with the exhaust port of said sleeve, and means for reciprocating said sleeve to coöperate with said power piston 80

for temporarily opening the exhaust after completion of the power portion of the out stroke of said piston, for closing the exhaust and opening the admission upon further outward travel of said piston, and for maintaining the admission and exhaust closed during the entire in stroke of said piston.

2. In a two-cycle explosive engine, the combination of a power cylinder, a sleeve slidably mounted therein, said cylinder and sleeve being provided with coöperating inlet and exhaust ports, a power piston reciprocatingly mounted within said sleeve and provided with a port coöperating with the exhaust port of said sleeve and with an inclined edge coöperating with the inlet and exhaust ports of said sleeve, and means for reciprocating said sleeve.

3. In a two-cycle explosive engine, the combination of a power cylinder, a sleeve slidably mounted therein, said cylinder and sleeve being provided with coöperating inlet and exhaust ports, a power piston reciprocatingly mounted in said sleeve and having an end flange provided with a port coöperating with the exhaust port of said sleeve, said flange having an inclined edge coöperating with the inlet and exhaust ports of said sleeve, and an eccentric on the engine shaft for actuating said sleeve.

In testimony whereof, I affix my signature, in presence of two witnesses.

HORATIO H. NEWMAN.
